UNITED STATES PATENT OFFICE.

ARTHUR NEAL KERR, OF TULSA, OKLAHOMA.

REFINING METHOD AND APPARATUS.

1,199,903.

Specification of Letters Patent.

Patented Oct. 3, 1916.

Application filed February 19, 1916. Serial No. 79,274.

To all whom it may concern:

Be it known that I, ARTHUR NEAL KERR, a citizen of the United States, residing at Tulsa, in the county of Tulsa and State of Oklahoma, have invented certain new and useful Improvements in Refining Methods and Apparatus, of which the following is the specification.

This invention relates to a method and apparatus for treating lighter runs of oil well products and particularly to a method and apparatus to treat casing-head gasoline, whereby all of said gasoline is utilized and separated and whereby the entire process of separation into various fractions may be carried out in a single operation.

Casing-head gasoline is made up of the following ingredients in approximately the proportions indicated:

20 Lubricating oil and burning oil	1 to 2½ %
60 B. naphtha	7 to 15 %
70 B. straight run gasoline	7 to 15 %
84-86 B	25 to 50 %
Tops 106-96 B	35 to 50 %

25 Prior methods of treatment and distillation have, in so far as I am aware, always resulted in the complete or substantial loss of the "tops."

30 It is an object of the invention to provide a method and apparatus for first distilling and then separating casing-head gasoline or the like, and in one operation employing its light fractions or "tops" to enliven a 35 low-grade product, thus increasing the value of such product and at the same time save the "tops."

It is another object of the invention to provide a method and apparatus where the 40 entire process of treatment of casing-head gasoline or the like may be carried out in a single operation and under very moderate pressure.

45 Other objects and advantages of the invention will appear as the description to follow proceeds.

In the drawings: Figure 1 is a plan view of an apparatus employed to carry out my new method. Fig. 2 is an elevation thereof.

50 In the drawings, 1 represents a steam still into which casing-head gasoline is pumped by suitable means and to which steam under moderate pressure, say from twenty to forty pounds, is supplied through pipe 2, distilling 55 the casing-head gasoline. The distillation products flow up the pipe 3 and through a

coil 4 in a vat 5, containing warm water and supported upon a platform 6 so as to be at a considerable elevation above the still 1. From the vat 5 the distillation products flow into a separation tank 7, from which the heavy condensates are drained back through the pipe 8 to the still, the volatile distillation products passing on through pipe 9 to the cooling vat 10, from which they pass through pipe 11 into tanks or containers 12, 13, 14, 15 and 16, as are now to be described.

The tank 13 contains an atomizer 14 in communication with the pipe 11 and is partially filled with naphtha or low grade product. The first run from the still (for the most part gas and products of 106° B. down) is sent past the tanks 12, 14 and 16 and into the atomizer 14, bubbling up into the tank 13 and being almost entirely and completely absorbed thereby with the exception of a small amount of gas escaping at safety valve 26. This process is carried on until the distillation product reaches 96° Baumé, whereupon the tank 13 is cut off by means of the stop cock 17, the product then running into the "84-86" tank 12, into which it runs until the distillation product reaches 72° B. Tank 12 is also equipped with safety valve 25 to relieve excess gas. The product obtained from the 84-86 is "gas machine" gasoline of average gravity 84-86° B. and is salable at a higher price than ordinary gasoline. After the product reaches 72° it is cut by means of the stop cocks 20, 21, 22, 23 and 24, into the tanks 14, 15 and 16, these tanks respectively receiving the distillation products down to 70-68 and 66, while still further tanks may be supplied as is perfectly obvious to receive lower grades, 64 and other grades of straight run gasoline.

It will be immediately seen that by the method hereinabove disclosed, the large amount of "tops" in casing-head gasoline is saved, and at the same time the value of the naphtha is increased and the entire process is carried on under moderate pressures and at a single operation.

105 I claim:

1. A method of treating casing-head gasoline which consists in distilling the same in a steam still under moderate pressure, in thereafter moderately cooling the products of distillation, in absorbing the light volatile distillate fractions in naphtha or the

like, and in grading the remaining fractions according to their nature, whereby all of the casing head gasoline will be treated in a single process and a low grade product simultaneously improved.

2. A method of treating gas well products which consists in passing casing head gasoline through a steam still to distil the same, moderately cooling the product of distillation running the light distillate in to a low grade product to be absorbed thereby and enrich the same and in thereafter separating and grading the heavier distillates.
3. A method of treating gas well products applicable under moderate pressures which consists in distilling casing head gasoline, passing the first run light fractions of the distillate in finely divided form into a low grade product to be absorbed thereby, in passing the later run products successively

into separate containers at predetermined Baumé gravities, substantially as described.

4. A method of treating gas well products which consists in passing light gasoline 25 through a moderate pressure still, permitting the distillation product to settle and cool, in running the first run light fractions down to approximately 96 Baumé into a low grade product in finely divided form to 30 be absorbed by the same, in cutting the product from approximately 96 to approximately 72 into a container and in cutting the heavier distillate into graded tanks substantially as described. 35

In witness whereof, I hereunto subscribe my name to this specification in the presence of two witnesses.

ARTHUR NEAL KERR.
